FINGER RING

Filed Sept. 28, 1925

FIG. 1.

FIG. 2.

FIG. 3.

INVENTOR:
Herman W. A. Goetzke
BY David E. Carlson
ATTORNEY.

UNITED STATES PATENT OFFICE.

HERMAN W. A. GOETZKE, OF NORTH ST. PAUL, MINNESOTA.

DESIGN FOR A FINGER RING.

Application filed September 28, 1925. Serial No. 14,932. Term of patent 14 years.

To all whom it may concern:

Be it known that I, HERMAN W. A. GOETZKE, a citizen of the United States, residing at North St. Paul, in the county of Ramsey and State of Minnesota, have invented a new, original, and ornamental Design for Finger Ring, of which the following is a specification.

In the accompanying drawing:—

Fig. 1 is a top plan view of a finger ring showing my new design.

Fig. 2 is a side view of Fig. 1.

Fig. 3 is an edge view of the ring.

I claim:

The ornamental design for a finger ring, as shown.

HERMAN W. A. GOETZKE.
